Primary Examiner — April Rivas

CLAIM

The ornamental design for a storage compartment for toiletries, as shown and described.

DESCRIPTION

FIG. 1 shows a perspective view of a storage compartment for toiletries;

FIG. 2 shows a front side view of the storage compartment for toiletries;

FIG. 3 shows a rear side view of the storage compartment for toiletries;

FIG. 4 shows a left side view of the storage compartment for toiletries;

FIG. 5 shows a right-side view of the storage compartment for toiletries;

FIG. 6 shows a top plan view of the storage compartment for toiletries; and,

FIG. 7 shows a bottom plan view of the storage compartment for toiletries.

The broken lines shown in the figures show portions of the storage compartment for toiletries which form no part of the claimed design.

The shade lines in the figures show contour and not surface ornamentation.

1 Claim, 5 Drawing Sheets
